PIANO

Sidney C. Shill, Los Angeles, Calif.

Application May 18, 1946, Serial No. 670,693

10 Claims. (Cl. 84—238)

1

This invention relates to musical instruments, particularly pianofortes of the general character embodied in my United States Letters Patent No. 2,377,582, issued to me on June 5, 1945.

In the above identified letters patent there is disclosed and claimed a horizontal, downstrike piano action whose elements are so structurally characterized and functionally related that the action will be extremely compact, and will be particularly adapted, although not necessarily, for use in a portable piano of such small dimensions as to fit in an airplane trunk or beneath a car or steamer berth, as well as be inexpensive and comparatively light in weight so as to promote wide-spread use of the instrument and convenient transportation thereof.

Furthermore, the instrument as disclosed and claimed in the above identified patent embodies the standard $\frac{3}{8}$ of an inch key dip and $1\frac{1}{8}$ inches hammer stroke; uses standard piano action parts; has the touch of a conventional action so that normal playing technique may be developed at the instrument; and whose parts are conveniently accessible and adjustable, with each key and hammer unit removable from the action for adjustment, inspection, or repair without disturbing other units.

The primary object of the present invention is to provide a piano action of the horizontal, downstrike hammer type which has all of the qualifications and advantages of the action disclosed in the aforesigned Patent No. 2,377,582, and, in addition, has operatively associated with its mechanism, a means which functions to restore the operative connection between the jack and hammer following playing of a note, during the return movement of the key to its playing position, and sufficiently prior to reaching such position, that repetition of the note may be effected with the surety and fidelity comparable to that obtainable with the expensive full scale actions of high class upright and grand pianos, whereby to compensate for the faulty technique of the pianist in failing to permit the key to return to its fully raised playing position after each playing of the note in executing a repetition or trilling passage, thus rendering the simply constructed and relatively inexpensive action of this invention capable of being used as the structural and functional musical equivalent, in an 88 note scale, of the more complicated and expensive actions of grand pianos, all to the end of enabling the cost of a high class instrument to be materially reduced, and the bulky grand piano to be superseded by a compact instrument of small

2

dimensions, having equivalent tone quality and performance.

It is another object of this invention to provide a horizontal, downstrike hammer type action with which the novel and simply constructed repetition device is operatively associated in a manner to obtain maximum efficiency in insuring the repeated playing of a note in response to depression of a partly raised key in executing a repetition or trilling passage, all without detracting from the ease of assembling and disassembling the key and hammer unit.

It is a further object of this invention to provide a piano action of the above described character in which the jack let-off or escapement function is performed by the repetition device so as to eliminate a separate let-off member or its equivalent as embodied in the aforesigned Patent No. 2,377,582, thus structurally simplifying the action without adversely affecting its mechanical efficiency.

With these and other objects in view, the invention resides in the combinations, arrangements and functional relationships of elements as set forth in the following specification and particularly pointed out in the appended claims.

In the accompanying drawings,

Figure 1 is a vertical, transverse sectional view through the key frame of a piano action embodying my invention, and illustrating in its normal position, a typical key and hammer unit;

Figure 2 is a view similar to Figure 1, and illustrating the key partly depressed to a position immediately in advance of that at which the let-off or escapement of the jack from the hammer takes place;

Figure 3 is a view similar to Figure 1, and illustrating the positions of the working parts immediately following the let-off of the jack from the hammer;

Figure 4 is a view similar to Figure 3, and illustrating the positions of the working parts at which the repetition mechanism functions to enable the operative connection between the jack and hammer to be restored with the key held in partly depressed position;

Figure 5 is an enlarged detail sectional view taken on the line 5—5 of Figure 1, and looking in the direction of the arrows;

Figure 6 is a vertical, transverse sectional view through the key frame of a second form of piano action embodying this invention, and illustrating in its normal position, a typical key and hammer unit;

Figure 7 is a view similar to Figure 6, and

illustrating the let-off position of the jack; Figure 8 is a fragmentary detail sectional view taken on the line 8—8 of Figure 6.

Referring specifically to the drawings, and particularly to Figures 1 to 5, inclusive, the piano action embodying this form of the invention comprises a key frame 10 having a center rail 11 supporting the balance key pins 12, on each of which latter is pivotally mounted approximately medially of its ends a key 13 for movement corresponding to the normal key dip of $\frac{1}{8}$ of an inch, from the normal raised playing position shown in Figure 1, to the fully depressed position shown in Figure 3. A front key pin 14 (Figure 1) co-acts with each key to confine same to its vertical movement.

At its inner end the top portion of the key 13 is cut away to leave a relatively narrow end portion 15 on which is supported a hammer flange 16 having a flat base 17 through which extends an opening 18 receiving a screw 19 threaded into the portion 15 of the key 13. Pivotally mounted on the flange 16 by means of a pin 20 is the shank 21 of a hammer 22. A wire spring 23 has one end coiled at 24 and anchored to the hammer flange 16. The other end and rounded end of the spring 23 seats in a longitudinal groove 25 in the hammer shank 21, and the spring urges the hammer 22 upwardly to its full raised position relative to its string 26, which, like all strings of the piano, is horizontally disposed at a level immediately below the key frame 10. As shown in Figure 1, the upward movement of the hammer under the action of the spring 23 is definitely limited by a felt 27. In its raised position, the heel portion 29 of the hammer head 30 is opposite to and slightly clears the felt 31 of a back check 32 whose wire 33 is rigidly anchored in the jack rail 38 and may be utilized to support the felt 27.

A jack flange 35 is provided with a longitudinal slot 36 through which passes a screw 37 into the jack rail 38 to mount the flange 35 for adjustment on the rail by means of a feed screw 39 threadedly mounted in an overhanging portion 40 of the rail to abut the end of the flange, all as shown in Figure 1. A jack 41 is pivotally mounted on the flange 35 by means of a pin 42, and a spring 43 co-acts with the jack spring wire 44 to urge the jack to the extreme position shown in Figure 1 wherein the free end of the jack abuts a knuckle 46 on the hammer shank as also shown in this Figure. To determine this extreme position, the spring 43 may be adjusted to become unloaded therat, or a stop (not shown) similar to that disclosed in my Patent No. 2,377,582 may be provided on the hammer shank.

A let-off rod 47 which may be optionally utilized as the aforesaid stop for the jack 41, is fixed to the portion 15 of the key 13 to clear the path of movement of the hammer shank 21, with the free end of the let-off rod disposed to engage and move the jack clear of the knuckle 46 when the key 13 has been depressed slightly less than the amount necessary for the hammer 22 to complete its "strike" of $1\frac{1}{8}$ inches, thus disrupting the operative connection between the key and hammer.

A damper 48 is secured to one end of a flexible lever 49 secured in a slot 50 in the key frame 10. A lift tape 52 is detachably connected at one end to the loop 53 of a lift wire 54 anchored in the portion 15 of the key 13. The other end of the tape 52 is passed through two openings in the lever 49 to lock the tape to the lever in any selected position of longitudinal adjustment.

The usual sustaining pedal bar 57 common to the damper 48 of all the strings 26, is arranged beneath the lever 49.

A repetition member in the form of a lever 59 of the first class is pivotally mounted directly above the hammer shank 21 at 61 on a flange 62 secured to the jack flange rail 38. The lever 60 is urged by a spring 63 to the extreme position shown in Figure 1 wherein the inner end of the lever engages the stop regulating button 64 of a screw 65 threadedly mounted in the rail 38 for adjustment to vary the extreme position of the lever in one direction. The outer end of the lever 60, which projects above the hammer flange 16, has threadedly mounted therein the adjusting screw 66 of a lift regulating button 67. In the present instance the button 67 is located for engagement by the upper end of the hammer flange 16 to move the lever against its spring 63 when the key 13 is depressed from its normal playing position, although it will be understood that means other than the hammer flange may be provided for this purpose.

In the playing position of the key 13 and the fully raised position of the hammer 22 shown in Figure 1, the repetition lever 60 rests against the knuckle 46 and against the stop regulating button 64 under the action of the spring 63, with the lift regulating button 67 spaced from the actuating means provided by the hammer flange 16, so as to function with respect to the key and hammer unit in a manner to be fully described in the operation of the invention which is as follows:

Initial depressing movement of the key 13 from the normal raised playing position shown in Figure 1, by pressure of the finger upon the outer end of the key, will raise the inner end of the key, and hence will raise the pivoted end of the hammer 22 directly mounted on the key by the flange 16. As the knuckle 46 on the hammer shank 21 is abutting the free lower end portion of the jack 41, movement of the hammer 22 towards the string 26 will be effected, as shown in Figure 2.

As depressing movement of the key approaches the position shown in Figure 2, the let-off rod 47 engages the jack 41, which latter is then pushed off of the knuckle 46 with but a relatively slight wiping motion against the knuckle when the hammer reaches a point about $\frac{1}{8}$ of an inch from the string, whereby to disrupt the operative connection between the key and hammer in order to prevent blocking of the hammer on the string.

It will be noted that in Figure 1 the damper lifting tape 52 is normally slack and is pulled taut by the key 13 during the aforesaid movement of the key, so as to lift the damper 48 from the string 26 just prior to striking of the latter by the hammer, whereby to render the string free to vibrate, as clearly shown in Figure 3. Upon the release of the key, the hammer spring 23 restores the hammer to its fully raised position in engagement with the felt 27, and the key returns by gravity to its playing position shown in Figure 1, thus permitting the jack spring 43 to restore the jack 41 to its normal position of Figure 1 and in operative relationship to the knuckle 46.

It will also be noted that although the back check felt 31 will be clear of the hammer in the normal raised playing position of the latter, and will not obstruct free movement of the hammer by the key, and in the other direction by the

spring 23, the back check will co-act with the heel portion 29 of the hammer head in preventing unintentional repeated striking of the string by the hammer should the key be held depressed. Under such conditions, the heel portion 29 of the hammer head will become jammed or wedged against the back check felt 31 during the return movement of the hammer by the spring 23, due to the fact that the hammer pivot 20 on the key moves closer to the back check during raising movement of the inner end of the key, all as shown in this figure. However, upon the release of the key with the attending movement of the hammer pivot 20 away from the back check 32, the hammer will instantly disengage the back check felt 31 so as to continue movement to its fully raised position under the action of the spring 23.

During this normal operation of the mechanism accompanied by a full release of the key 13 after each playing of a note, the repetition lever 60 is rocked idly about its pivot 61 on the flange 62, in one direction by engagement of the hammer flange 16 with the lift regulating button 67 to move the lever 60 off of the knuckle 46 on which it normally rests as shown in Figure 1, and in the other direction by the repetition lever spring 63 to engage the lever with the stop regulating button 64, as also shown in Figure 1.

However, should the pianist fail as a result of faulty technique in executing a repetition or trilling passage, to fully release the key, following playing of a note, the repetition lever 60 functions to restore the operative connection between the jack 41 and hammer 22 following the let-off operation, with the key held in partly depressed position, thus enabling repetition or trilling to be effected.

In this connection, it will be noted that during initial depressing movement of the key from its normal raised playing position of Figure 1, the hammer flange 16 engages the lift regulating button 67 of the repetition lever 60 to move the latter off of the knuckle 46 as previously described, and away from the stop regulating button 64 against the action of the spring 63 as shown in Figure 2, all so as to prevent the repetition lever from interfering with the subsequent let-off of the jack 41 from the hammer 22.

As depressing movement of the key approaches the position shown in Figure 3, the let-off rod 47 engages the jack 41 and pushes the latter off of the knuckle 46 to disrupt the operative connection between the jack and hammer in order to prevent blocking of the latter on the string as also previously described. With the key held fully depressed, and the hammer rebounding from the string, its knuckle 46 will strike the repetition lever 60 so as to move same slightly against the action of the spring 63, concurrently with which the heel portion of the hammer head 30 jams against the back check, all as shown in Figure 3.

As the key is released, the hammer is freed from the back check 32 so as to permit the hammer spring 23 to move the hammer upwardly. However, under the action of the spring 63 of the repetition lever 60, force is exerted upon the hammer through the knuckle 46 to delay the return movement of the hammer to its normal position sufficiently for the jack spring 43 to restore the jack to its position of operative engagement with the hammer knuckle 46 even though the key is not fully released and is only raised approximately $\frac{1}{2}$ of the key dip.

Thus, by fully depressing the key from this

partly raised position, the hammer will co-act with the jack to again strike the string, whereby to compensate for faulty technique of the pianist in failing to fully release the key for its return to its normal raised playing position before again depressing the key to execute a repetition or trilling passage.

From the foregoing description, it will be clear that the repetition lever 60, although actively functioning at any time that the key is not permitted to return to its normal raised playing position, has no adverse effect on the normal operation of the mechanism as results from the full return movement of the key, as under such normal operation the hammer spring 23 restores the hammer to its fully raised position in engagement with the felt 27, and the key returns by gravity to playing position, thus permitting the jack spring 43 to restore the jack 41 to its position in operative relation to the knuckle 46.

Reference will now be had to Figures 6, 7 and 8 which illustrate a second form of piano action embodying this invention, structurally differing from the form of the invention previously described, by omitting the separate let-off member 47. The jack let-off or escapement function of the let-off member 47 is accomplished by a means embodied in a control or repetition member 60a. The member 60a not only performs the previously described function of the repetition member 60 in enabling repetition to be effected by fully depressing a key from a partly depressed position, but also actuates the jack 41 to disrupt its operative connection to the hammer 22 before the hammer strikes the string 26, in order to prevent blocking of the hammer on the string.

The control member 60a is identical in construction to the repetition member 60 with the sole exception that a let-off portion in the form of a lateral or transverse shoulder 60b is provided on the member 60a at a location to be engaged by and form a stop for the jack 41 in the normal position of the action shown in Figure 6. Thus, the jack will be in the path of movement of the shoulder 60b when the control member is raised by the hammer flange 16 in response to depression of the key 13, as previously described and illustrated in Figure 2.

When the key 13 is depressed from its normal playing position shown in Figure 6, and reaches the let-off position shown in Figure 7, the hammer flange 16 and lift regulating button 67c of the control member 60a will have moved the latter sufficiently for its let-off shoulder 60b to shift forwardly in its arc of movement, the amount required to disengage the jack 41 from the knuckle 46, in order to prevent blocking of the hammer on the string.

It will be clear that the let-off and repetition functions of the control member 60a are accomplished in the same timed relationship as are the respective functions of the previously described let-off member 47 and repetition member 60, and that the control member 60a also has no adverse effect upon the normal operation of the mechanism as results from the full return movement of the key.

I claim:

1. In a pianoforte, a horizontal action of the downstrike hammer type comprising: a key; a hammer; means pivotally mounting the hammer on the key for movement downwardly to strike a string; a spring urging the hammer upwardly to an extreme position; a jack; a spring urging the jack to an operative position wherein it will effect downward movement of the hammer in

response to depression of the key; means for freeing the hammer from the jack when the hammer has reached a predetermined position in its downward movement; a repetition member; means pivotally mounting the repetition member above the hammer; means urging the repetition member in a direction wherein the member will tend to urge the hammer downwardly; means limiting movement of the repetition member by the urging means to a position wherein the repetition member will be prevented from urging the hammer downwardly when the key occupies its normal playing position; said repetition member being disposed to engage the hammer and impose the force of said urging means downwardly upon the hammer should the key be held partly depressed following playing of a note, so as to delay upward movement of the hammer until the jack has returned to its operating position, whereby to enable repetition of the note to be effected by fully depressing the key from said partly depressed position.

2. In a pianoforte, a horizontal action of the downstrike hammer type comprising: a key; a hammer; means pivotally mounting the hammer on the key for movement downwardly to strike a string; a spring urging the hammer upwardly to an extreme position; a jack; a spring urging the jack to an operating position wherein it will effect downward movement of the hammer in response to depression of the key; means for freeing the hammer from the jack when the hammer has reached a predetermined position in its downward movement; a repetition member; means pivotally mounting the repetition member above the hammer; means urging the repetition member in a direction wherein the member will tend to urge the hammer downwardly; means limiting the movement of the repetition member by the urging means to a position wherein the repetition member will be prevented from urging the hammer downwardly when the key occupies its normal playing position; means on the key engageable with the repetition member to move same against its urging means during initial depression of the key, sufficiently to remove from the hammer, any downward pressure imposed thereon by the repetition member, so that the latter will not interfere with the let-off operation; said repetition member being disposed to engage the hammer and impose the force of said urging means upon the hammer should the key be held partly depressed following playing of a note, so as to delay upward movement of the hammer until the jack has returned to its operating position, whereby to enable repetition of the note to be effected by fully depressing the key from said partly depressed position.

3. In a pianoforte, a horizontal action of the downstrike hammer type comprising: a key; a hammer; means pivotally mounting the hammer on the key for movement downwardly to strike a string; means urging the hammer upwardly to an extreme position; a jack; means urging the jack to an operating position wherein it will effect downward movement of the hammer in response to depression of the key; means for freeing the hammer from the jack when the hammer has reached a predetermined position in its downward movement; a back check supported in such fixed position that should the key be held depressed, the hammer will, during its upward movement, wedge itself against the back check to prevent repeated striking of the string; the relation of the back check to the hammer pivot being

such that upon return movement of the key to playing position, the hammer pivot will move away from the back check sufficiently for the hammer to free itself from the back check and be restored by its urging means to said extreme position; a repetition member; means pivotally mounting the repetition member above the hammer; means urging the repetition member in a direction wherein the member will tend to urge the hammer downwardly; means limiting the movement of the repetition member by the urging means to a position wherein the repetition member will be prevented from urging the hammer downwardly when the key occupies its normal playing position; said repetition member being disposed to engage the hammer and impose the force of the member-urging means downwardly upon the hammer should the key be held partly depressed following playing of a note, so as to delay upward movement of the hammer until the jack has returned to its operating position, whereby to enable repetition of the note to be effected by fully depressing the key from said partly depressed position.

4. In a pianoforte, a horizontal action of the downstrike hammer type comprising: a key; a hammer; means pivotally mounting the hammer on the key for movement downwardly to strike a string; means urging the hammer upwardly to an extreme position; a jack; means urging the jack to an operating position wherein it will effect downward movement of the hammer in response to depression of the key; means for freeing the hammer from the jack when the hammer has reached a predetermined position in its downward movement; a repetition lever; means pivotally mounting the repetition lever intermediate its ends above the hammer for rocking movement about a fixed axis, a spring urging the repetition lever in a direction wherein the lever will engage the hammer to urge same downwardly; means co-acting with one end portion of the lever to limit its movement by its spring to a position wherein the lever will be prevented from urging the hammer downwardly when the key occupies its normal playing position; and means on the key co-acting with the other end portion of said lever to move same against its spring during initial depression of the key, sufficiently to remove from the hammer, any downward pressure imposed thereon by the repetition lever; said lever being operable to impose the force of its spring downwardly upon the hammer should the key be held partly depressed following playing of a note, so as to retard upward movement of the hammer sufficiently for the jack to return to its operating position with the key in its said partly depressed position, whereby to enable repetition of the note to be effected by fully depressing the key from said partly depressed position.

5. In a pianoforte, a horizontal action of the downstrike hammer type comprising: a key; a hammer; means pivotally mounting the hammer on the key for movement downwardly to strike a string; a spring urging the hammer upwardly to an extreme position; a jack mounted for pivotal movement above the hammer; a spring urging the jack into operative engagement with the hammer for downward movement of the hammer by the jack in response to depression of the key; means for freeing the hammer from the jack when the hammer has reached a predetermined position in its downward movement; a repetition member; means pivotally mounting said member above the

hammer; a spring urging said member in a direction wherein the member will tend to urge the hammer downwardly; a stop limiting movement of said member by said spring to a position wherein the member will be prevented from urging the hammer downwardly when the key occupies its normal playing position; said member being disposed to engage the hammer and impose the force of said spring downwardly upon the hammer should the key be held partly depressed following playing of a note, so as to delay upward movement of the hammer until the jack has returned to its operating position, whereby to enable repetition of the note to be effected by fully depressing the key from said partly depressed position.

6. In a horizontal action of the downstrike hammer type, a key; a hammer pivotally mounted on the key for movement downwardly to strike a string, and urged upwardly to an extreme position; a jack mounted above the hammer and urged into operative engagement therewith for downward movement of the hammer by the jack in response to depression of the key; means for freeing the hammer from the jack when the hammer has reached a predetermined position in its downward movement; a repetition member; and means urging said member to impose a downward force upon the hammer should the key be held partly depressed following playing of a note, so as to retard upward movement of the hammer until the jack has returned to its operative position with the key in said partly depressed position, whereby to enable repetition of the note to be effected by fully depressing the key from said partly depressed position.

7. In a horizontal action of the downstrike hammer type, a key; a hammer pivotally mounted on the key for movement downwardly to strike a string, and urged upwardly to an extreme position; a jack mounted above the hammer and urged into operative engagement therewith for downward movement of the hammer by the jack in response to depression of the key; a repetition member; means urging said member to impose a downward force upon the hammer should the key be held partly depressed following playing of a note, so as to retard upward movement of the hammer until the jack has returned to its operative position with the key in said partly depressed position, whereby to enable repetition of the note to be effected by fully depressing the key from said partly depressed position; and let-off means on the repetition member co-acting with the jack to move same out of operative engagement with the hammer when the latter has reached a predetermined position in its downward movement, so as to prevent blocking of the hammer on the string.

8. In a horizontal action of the downstrike hammer type, a key; a hammer pivotally mounted on the key for movement downwardly to strike a string, and urged upwardly to an extreme position; a jack mounted above the hammer and urged into operative engagement therewith for downward movement of the hammer by the jack in response to depression of the key; a repetition member; and means urging said member to impose a downward force upon the hammer should the key be held partly depressed following playing of a note, so as to retard upward movement

of the hammer until the jack has returned to its operative position with the key in said partly depressed position, whereby to enable repetition of the note to be effected by fully depressing the key from said partly depressed position; said member having a let-off and stop shoulder engaged by the jack to move same out of operative engagement with the hammer when the latter has reached a predetermined position in its downward movement, so as to prevent blocking of the hammer on the string.

9. In a horizontal action of the downstrike hammer type, a key; a hammer pivotally mounted on the key for movement downwardly to strike a string, and urged upwardly to an extreme position; a jack mounted above the hammer and urged into operative engagement therewith for downward movement of the hammer by the jack in response to depression of the key; a repetition member; means pivotally mounting the repetition member above the hammer; means urging said member in a direction wherein the member will tend to urge the hammer downwardly; means limiting movement of said member by the urging means to a position wherein said member will be prevented from urging the hammer downwardly when the key occupies its normal playing position; means on the key engageable with the repetition member to move same against its urging means during initial depression of the key; and means on the repetition member engaging the jack and responsive to said movement of the repetition member by the key, to move the jack out of operative engagement with the hammer when the latter has reached a predetermined position in its downward movement.

10. In a horizontal action of the downstrike hammer type, a key; a hammer pivotally mounted on the key for movement downwardly to strike a string, and urged upwardly to an extreme position; a jack mounted above the hammer and urged into operative engagement therewith for downward movement of the hammer by the jack in response to depression of the key; a repetition member; means pivotally mounting said member above the hammer; means urging said member in a direction wherein the member will tend to urge the hammer downwardly; means limiting movement of said member by the urging means to a position wherein said member will be prevented from urging the hammer downwardly when the key occupies its normal playing position; means on the key engageable with said member to move same against its urging means during initial depression of the key; and a let-off-stop shoulder on said member engaged by the jack and responsive to said movement of the member by the key, to move the jack out of operative engagement with the hammer when the latter has reached a predetermined position in its downward movement.
